chinery Corporation, Paterson, N. J., a corpora-
tion of New Jersey

Application November 16, 1932, Serial No. 642,920

111 Claims. (Cl. 12—47)

The present invention relates to heel breeding machines and is illustrated as embodied in a machine for breeding heels attached to their shoes.

5 The breeding of heels attached to their shoes is an extremely critical operation because of the variations in the heights of heels, variations in the heights of lasts and variations in the thickness of the sole materials in line with the breeding knife, all of which make it difficult to effect an adjustment of the breeding knife whereby the knife will cut a chip from the heel breast without penetrating the shank of the shoe. An object of the present invention is to 10 provide a heel breeding machine which may be depended upon to cut completely through the breast of an attached heel without injuring the shank of the shoe.

In order to measure the stroke of the breeding knife to cause the knife to come to rest accurately positioned at the base of the heel, it is proposed by the present invention to provide a measuring means arranged to operate in advance of the knife stroke whereby the termination of 15 the knife stroke may be arranged to occur as the driving mechanism comes to the bottom of its stroke, thus obviating the possibility of the knife being carried beyond the base of the heel. With this in view, a feature of the invention 20 contemplates the provision, in a heel breeding machine, of a breeding knife and a knife actuator arranged to provide a variable lost motion between the actuator and the knife at the beginning of the stroke of the actuator.

25 In order that the stroke of the breeding knife may terminate with the knife positioned accurately at the base of the heel to be breasted, it is further proposed to provide means operating in advance of the knife stroke for gaging the 30 limit of the knife stroke from the shank of the shoe to be breasted, and in accordance with a feature of the invention, there are provided a shank engaging means and connections between said shank engaging means and the knife actuator for predetermining the position from which 35 the actuator operates.

It is further proposed to employ a shank engaging member to measure the extent of the breeding cut, and to that end and in accordance 40 with a feature of the invention the illustrated heel breeding machine is provided with connections from the shank engaging member to the knife actuator for measuring, in advance of the knife stroke, the effective stroke of the actuator.

45 55 It is desirable that the elevation of the heel

remain unchanged during the knife stroke in order that the knife may come to rest with its cutting edge accurately positioned at the base of the heel. To this end, it is proposed that the sole materials in line with the breeding knife be compressed prior to the knife stroke sufficiently to take all of the yield therefrom and to bring them down firmly on to the last in order that they may remain fixed during the knife stroke and not subject to depression by the thrust of the knife. In order to effect this result it is proposed to apply pressure to the shank and, accordingly, a feature of the invention consists in the provision in a heel breeding machine of a shank presser, means energized by the next preceding cycle of the machine and normally disconnected from said presser for applying pressure thereto, and means for connecting said presser to said pressure applying means at the beginning of the power cycle.

It is desirable that the application of pressure be timed to take effect in advance of the actuation of the breeding knife in order that the stroke of the knife may be measured after the elevation of the shank has been fixed. With this in view an object of the invention is so to organize the power pressure means with relation to the knife and its operating mechanism that the stroke of the knife will not commence until after the power pressure has been effected.

Accordingly, a feature of the invention consists in timing the application of pressure to the shank presser to take effect before the stroke of the actuator commences.

It is proposed to apply clamping pressure to the tread of the heel to be breasted as well as to the shank of the shoe and to that end, a feature of the invention consists in the provision in a heel breeding machine of a shank presser, a presser post, a heel tread plate, a heel plate 40 post, and means for applying distributed power-produced pressure to said posts. It is desirable that these pressures be equal in order that there may be no misplacement of the shoe upon the jack as a consequence of the power pressure and accordingly, means for effecting the application of such equal pressures constitutes a further feature of the invention.

In heel breeding machines now in commercial use the breeding position of the shoe is determined by gaging the heel relatively to a heel tread plate which plate has been adjusted to bring its forward edge into alignment with the breeding knife. It is not practicable in such machines to gage the shoe relatively to the knife

- itself because of the fact that the knife comes to rest at an elevation relatively remote from the heel tread of a shoe to be breasted. It is proposed to provide means for varying the retracted position of the breasting knife in order that the knife may come to rest at an elevation, relatively to the tread of the heel to be breasted, which will permit gaging of the breasting position of the shoe relatively to the breasting knife.
- 10 Accordingly a feature of the invention contemplates the provision in a heel breasting machine of a knife slide in which the breasting knife is mounted, yielding means for holding the knife slide in retracted position, and means for adjusting the retracted position of the slide whereby the knife may be located at an elevation such that the breasting position of a shoe may be accurately gaged thereby.
- 15 It is of the utmost importance that the positioning of a shoe, preliminary to the heel breasting operation thereon, consume the least possible time, and it is an object of this invention so to organize the jack and its supporting mechanism that the positioning of a shoe may be quickly and conveniently effected. Accordingly, a feature of the invention contemplates the provision in a heel breasting machine of a shoe supporting jack yieldingly supported and arranged for straight-line movement to and from operative position.
- 20 It is an object of the invention to provide for a lateral movement of the shoe in order to permit the shoe to be brought into proper alignment with the breasting knife. To this end there is provided, in accordance with a feature of the invention, a jack carrier arranged to permit rotation of the jack about a horizontal axis extending longitudinally of the jack and shoe bottom engaging means for clamping a shoe on 25 the jack and thus holding the jack from rotating during the breasting operation.
- 25 In order to permit the shoe bottom to be maintained in a horizontal position during the swinging of the jack about its horizontal axis it is desirable that the shoe be mounted on the jack with capacity for a limited rocking movement about the toe and heel supports and it is also desirable that an auxiliary support be provided for maintaining such horizontal arrangement of the shoe and relieving the operator of the burden of holding the shoe in position on the jack after the jack has been brought into operative position. Accordingly, a feature of the invention consists in the provision in a heel breasting machine of shoe supporting means comprising a toe support, a heel support and a heel stop arranged partially to embrace the back of a heel to be breasted.
- 30 In order to secure the shoe in position to be operated upon by the breasting knife it is proposed to employ, as one of the clamping members, a heel stop which may, or may not, be the stop employed as an auxiliary shoe support, and accordingly there is provided, in accordance with a feature of the invention, means for clamping a shoe upon the jack comprising a shank presser, a heel tread plate and a heel stop.
- 35 It is usual for the breasting knife to be beveled on its forward surface. If the knife is required to remove a substantial chip from the heel, as is usually the case, the engagement of the chip with the beveled surface of the knife urges the knife away from its prescribed path of movement. If the knife is securely held so that it
- 40 cannot spring away from its path of movement

the engagement of the chip with the beveled surface of the knife tends to tilt the shoe backwardly upon the last pin. It has been found that such tilting of the shoe makes it difficult to produce a straight, smooth breasting cut. In order to produce a straight, clean cut which will require only a minimum of scouring to produce a finished heel breast, it is proposed to eliminate the tendency of the shoe to tilt backwardly upon the last pin by locking a heel stop in heel engaging position and thus preventing any backward movement of the heel. Accordingly, a feature of the invention contemplates the provision in a heel breasting machine of a heel stop arranged to engage the back of a heel to be breasted, and means actuated by the cutting thrust of the breasting knife for locking the heel stop in heel engaging position.

These and other features of the invention will appear more fully from the following detailed description when read in connection with the accompanying drawings and will be pointed out in the appended claims.

In the drawings,

Fig. 1 is a front elevation of a machine embodying this invention;

Fig. 2 is an enlarged side elevation of the upper portion of the machine;

Fig. 3 is an enlarged side elevation of the lower portion of the machine;

Fig. 4 is a horizontal section taken substantially on the line IV—IV of Fig. 2, with certain parts at the front of the machine broken away;

Fig. 5 is an enlarged fragmentary view of certain parts in the head of the machine;

Fig. 6 is a detail view of a heel stop;

Fig. 7 is a sectional elevation taken substantially on the line VII—VII of Fig. 3;

Fig. 8 is a fragmentary plan view on the same scale as Fig. 2 illustrating certain parts in the head of the machine;

Fig. 9 is a perspective view of a heel tread plate and its carrying member;

Fig. 10 is a fragmentary vertical section through the center of a heel which is being breasted;

Figs. 11 to 14, inclusive, are fragmentary views illustrating parts of the knife actuating mechanism in successive positions during the cycle of operation; and

Fig. 15 is a vertical section taken substantially on the line XV—XV of Fig. 4.

The invention is illustrated as embodied in a machine for breasting heels after they are attached to their shoes. The breasting knife 20 is power actuated by a motor 22 (Fig. 1) through suitable connections including a constant stroke knife actuator 24 arranged to impart a variable stroke to a knife slide comprising a knife supporting cross head 54 and a pair of parallel bars 56 to which the cross head is secured. The variation in the knife stroke is effected by providing a variable lost motion at the beginning of the stroke of the actuator. The extent of the knife stroke is predetermined by measuring means comprising a shank presser 26 (Fig. 10) arranged to engage the shank at a location substantially adjacent to the heel to be breasted and connections between the shank presser and the knife actuator 24 for measuring in advance of the stroke of the actuator the extent of its lost motion.

A shoe to be breasted is mounted upon a jack 28 (Fig. 2) supported upon a jack carrier 30

(Fig. 4) and arranged for straight line horizontal movement relatively to the carrier in order to move the shoe to and from position to be operated upon by the breasting knife, hereinafter referred to as the breasting position. The shoe is securely clamped upon the jack by the shank presser 26 and a heel tread plate 32 (Figs. 9 and 10) to which equal pressures are applied by a power compressed spring 34 (Fig. 1) through connections hereinafter described. The shoe is clamped at the back of the heel against a heel stop 36 (Figs. 6 and 10) arranged to be locked in heel engaging position in order to prevent any tilting of the shoe about the last pin during the breasting cut. The shoe supporting jack 28 is clamped in breasting position by the pressure applied to the shank presser 26 and the heel plate 32, and this pressure is also employed to actuate the devices for locking the heel stop 36 in heel engaging position.

The motor 22 transmits power to the breasting knife 20 through a combined driving wheel and balance wheel 38 (Fig. 3) and mechanism comprising a driving shaft 40 arranged to be connected to the wheel by a one revolution clutch mechanism 300, a crank pin 42 formed integrally with the driving shaft at its forward end, and connections between the crank pin and the knife actuator 24 comprising a screw 44 pivoted to the actuator, a wing nut 46 carried by said screw, and a connecting link or yoke 48 arranged to arrest the rotation of the nut and connect the nut and the crank pin 42. The breasting knife 20 is retracted and maintained in retracted position by a torsion spring 50 (Fig. 1) arranged to impart an upward pressure to the knife actuator 24 and through the actuator to the knife slide.

Referring particularly to the breasting knife and its actuating mechanism, as shown in Fig. 1, the knife is mounted upon a cross head 54 secured to the parallel vertical bars 56. Near their lower ends the bars 56 are provided with guideways in the form of grooves 66 for the reception of the actuator 24. The cross head 54 is arched somewhat and has provided in its front face recess 57 extending upwardly from its lower edge to provide clearance for the breasting knife. The cross head 54 is also provided with knife supporting brackets 59 extending downwardly and inwardly from opposite sides of the cross head into position to engage opposite sides of the breasting knife 20. The breasting knife has sliding engagement within grooves formed in plates 58 and 60 removably secured to the brackets 59. In order to expedite the removal of the breasting knife, the edge of the plate 58 adjacent to the cross head 54 is arranged to engage a shoulder in the cross head 54 arranged at a slight angle to the side of the breasting knife, and the plate 58 is provided with a slot 62 for the reception of a clamping screw 64 which slot is arranged in parallel relation to said shoulder in order to permit the plate 58 to move into and out of position to engage the breasting knife. In order to afford a vertical adjustment of the breasting knife an adjusting screw 65 is provided having interlocking engagement with the upper end of the breasting knife. At their upper ends the parallel bars 56 are slidably mounted in brackets 68 located at the head of the machine column 70 and diverging forwardly therefrom. At their lower ends the parallel bars 56 are slidably mounted in brackets 72 located approximately midway of the height of the

machine column and diverging forwardly therefrom at the same angle as the brackets 68.

The knife actuator 24 has a constant stroke imparted thereto by the crank pin 42 (Figs. 1 and 3) which acts through the connecting link 48 or yoke 48, wing nut 46 and screw 44 as above described. The screw 44 is pivoted on a stud 45 secured to the actuator 24. The connecting link 48 is pivotally mounted upon the crank pin 42 and has upwardly extending arms (Fig. 1) which curve outwardly for the reception of the wing nut therebetween. A clamping block 76 (Fig. 1) is secured to the upper ends of the arms for clamping engagement with the wing nut 46. The clamping block 76 is slidably supported upon the square head 77 of the screw 44 by gibs 78 (Fig. 7) formed integrally with the clamping block 76 and extending upwardly therefrom into position to engage the head of the screw 44 at its corners. The clamping block 76 has a central opening formed therein to provide clearance for the screw 44, and the gibs 78 are arranged to provide clearance for the screw 44 and for the actuator 24. The head 77 of the screw 44 is slotted to embrace the actuator (Fig. 3).

As herein illustrated the actuator is in the form of a cross head slidably mounted in grooves 66 formed in the parallel bars 56. The actuator is normally held at the limit of its elevation by the torsion spring 50 and connections between the springs and the actuator comprising a pair of links 80 cupped at their lower ends to receive the outspread and upturned ends of the torsion spring. At their upper ends the links 80 are pivoted on the stud 45 projecting forwardly from the actuator. The torsion spring is preferably carried by a sleeve 51 (Fig. 3) journaled on the hub 53 of the connecting link 48 and is confined between the link and a disk 55 secured to the end of the crank pin 42. In its elevated position the actuator supports the breasting knife assembly by engagement with the parallel bars 56 at the upper extremities of the grooves 66 (Fig. 1).

In order that the actuator, which has a constant stroke, may impart to the breasting knife a variable stroke the extent of which is determined in advance of the stroke of the actuator, means is provided for adjusting the actuator in the direction of its stroke in order to provide a measured lost motion at the beginning of the stroke of the actuator. In the illustrated machine the adjustment of the actuator operates to measure a distance between the actuator and the lower extremities of the grooves 66 which distance is equal to the difference between the extent of the stroke of the actuator and the extent of the required breasting cut. The adjustment of the actuator is arrested by the engagement of the shank presser 26 with the shank of the shoe to be breasted. During the adjustment of the actuator the breasting knife assembly descends with the actuator until said assembly is arrested by engagement of the edge of the knife with the heel tread, and during the remainder of its adjustment the actuator travels downwardly through the grooves 66 and comes to rest with the bottom of the actuator a predetermined distance above the lower extremities of the grooves 66 which distance determines the extent of the lost motion of the actuator. The point at which the actuator comes to rest is determined by the engagement of the shank presser 26 with the shank of the shoe to be breasted. Thus it will be seen that the lost

motion of the actuator is accurately measured by the engagement of the shank presser 26 with the shank of the shoe to be breasted. The extent of the lost motion may be varied by a vertical adjustment of the breasting knife relatively to the knife supporting cross head 54 whereby the engagement of the edge of the knife with the heel tread may be gaged to take effect at the desired point in the adjustment of the knife actuator.

Should the weight of the knife assembly be sufficient to cause a slight penetration of the heel by the breasting knife as it comes to rest on the heel tread, such penetration of the heel by the breasting knife would be inconsequential since the descent of the knife incidental thereto would be accompanied by a like descent of the shank presser thereby reducing that descent of the shank presser which occurs after the breasting knife comes to rest on the heel tread and proportionally increasing the lost motion of the actuator. Such increase of lost motion would, of course, be followed by a corresponding decrease in the effective stroke of the actuator. It will thus be seen that a penetration of the heel tread by the breasting knife as it comes to rest thereon cannot throw out of adjustment the devices for measuring the knife stroke.

The adjustment of the actuator, above referred to, is arrested at the end of the spring clamping of the shank presser hereinafter described and in advance of the locking of the wing nut 46 which operates to connect the crank pin 42 to the actuator. Consequently the elevation of the actuator at the beginning of its stroke is determined by the final elevation of the bottom of the shank of the shoe to be breasted. The length of the stroke of the actuator being constant, it follows that the limit of said stroke is also determined by the final elevation of the shank and, consequently, the limit of the knife stroke is likewise so determined. It follows that the knife, when properly adjusted by the hand screw 65, will come to rest with its cutting edge positioned accurately at the base of the heel.

Referring now more particularly to the construction of the illustrated machine, the adjustment of the actuator is effected by the successive operation of the treadle 90 and the spring clamping mechanism hereinafter described. The treadle 90 depresses the actuator 24 through connections comprising a treadle spring 92 (Fig. 1) and a foot piece 88 mounted in the lower end of a post 84 and arranged to rest on the hub of one of the links 80. The treadle spring 92 connects the lower end of the post 84 to a lug 94 formed in the treadle 90, the post 84 being slidably mounted in a sliding head 86 which forms a part of the power clamping mechanism. The stroke of the actuator 24 is effected by the crank pin 42 at the forward end of the driving shaft through connections hereinbefore described. In order that the adjustment of the actuator may be limited by the engagement of the presser 26 with the shank of the shoe to be breasted, the presser is mounted in the post 84 through which the adjustment of the actuator is effected. As the treadle 90 is depressed the post 84 slides downwardly through the sliding head 86 and the foot piece 88 depresses the actuator 24 against the resistance of the torsion spring 50. The breasting knife assembly moves downwardly with the actuator 24 and the post 84 until the downward movement of the knife assembly is arrested by the engagement of the

knife 20 with the tread face of the heel. The shank presser 26 being secured to the post 84, the knife 20 and the shank presser move downwardly in unison during the first stage of the depression of the treadle 90 and consequently their relation to each other is unchanged until the downward movement of the knife is arrested by its engagement with the heel of the shoe. Continued depression of the treadle thereafter causes the shank presser to move downwardly relative to the breasting knife and causes a movement of the actuator 24 relatively to the parallel bars 56 of the knife assembly as permitted by the grooves 66 in the bars 56 in which the ends of the actuator are arranged to slide vertically.

Referring now to the screw 44 and the wing nut 46,—during the depression of the actuator the screw 44 passes through the wing nut 46 and the nut spins upon the screw in order to accommodate itself to such movement thereof, the pitch of the screw threads being such that the screw may pass freely through the nut while the nut is maintained at a fixed elevation. The wing nut 46 may be supported in any convenient manner. In the illustrated machine means for supporting the nut consists of an arm 96 (Fig. 1) pivoted to an extension of the connecting link 48, a yoke 98 pivotally mounted on the arm and arranged to embrace the hub of the wing nut 46, and a pair of rolls 100 (Fig. 7) carried by the ends of the yoke 98 and extending inwardly therefrom into a concentric groove formed in the hub of the wing nut, said rolls acting as carriers for the nut and permitting the nut to be rotated freely by the screw 44 as it passes therethrough. The wing nut 46 is normally held in contact with the under surface of the clamping block 76 by a coiled spring 102, (Fig. 1) the lower end of which is mounted on the forward extension of a pivot pin 104 (Fig. 3) upon which the yoke 98 is mounted and the upper end of which is mounted upon a stud 106 extending forwardly from the clamping block 76. In order to hold the nut 46 out of contact with the clamping block 76 during the depression of the shank presser 26 a cam 108 is secured to the free end of the arm 96 and arranged to engage a roll 110 carried by the disk 55 secured to the crank pin 42, the free end of the arm 96 being offset forwardly to bring the cam 108 into position to engage the roll 110 (Fig. 3). The cam 108 is so arranged relatively to the roll that the machine comes to rest with the rise of the cam in contact with the roll, and the rise of the cam is extended sufficiently to hold the wing nut 46 out of contact with the clamping block 76 until the power compression of the shank presser 26 has been effected. As the roll 110 rides off the rise of the cam 108 the spring 102 swings the arm 96 about its pivot and brings the clamping surface of the wing nut into contact with the under surface of the clamping block 76. Downward movement of the clamping block after the wing nut has been thus brought into contact therewith clamps the nut and the block, thus completing the connection between the crank pin 42 and the actuator 24 whereby a constant stroke is imparted to the actuator.

It is desirable that the shank presser be arranged to engage the shank of the shoe to be breasted close up to the breast of the heel and it is also desirable that the shank presser be arranged for self adjustment to varying inclinations of shanks. In the illustrated machine the

shank presser (Figs. 2, 5 and 10) consists of a foot piece 26 mounted at the lower end of a bracket 114 secured to a cross pin 116 in the head of the presser post 84 and extending from said cross pin inwardly toward the plane of the jack, then downwardly and rearwardly to position the foot piece 26 close up to the heel breast. In order to prevent any misplacement of the shank presser during the power compression of the shank a guard 118 is formed integrally with the bracket 114 and carried outwardly therefrom and rearwardly into a position to engage the presser post 84 at the side of said post remote from the foot piece 26. In order to provide for self adjustment of the foot piece to varying inclinations of shanks connections are provided between the foot piece and the bracket 114 permitting a swinging movement of the foot piece about a center located on the shank engaging surface of the foot piece at a central point transversely thereof. Said connections comprise a cross pin 120 carried by the lower end of the bracket 114 and arranged for engagement within arcuate slots 122 formed in lugs 124 extending upwardly from the foot piece 26 and positioned at opposite sides of the bracket 114, the axes of said arcuate slots being located in the shank engaging surface of the foot piece. The foot piece 26 is confined to movement about the axes indicated by interengaging arcuate surfaces formed in the foot piece and in the bracket 114 respectively.

In order to clamp the shoe to be breasted securely upon the shoe supporting jack 28 after it has been brought into breasting position, clamping means are provided comprising the shank presser 26, the heel tread plate 32 and the heel stop 36 (see Fig. 10). The heel tread plate 32 may be of ordinary construction, the forward edge of the plate having a relatively slight curvature in order that the center of the forward edge may be positioned substantially adjacent the path of the breasting knife regardless of the degree of curvature of the knife. It is apparent that the path of the breasting knife at the central portion of the knife will vary as the curvature of the knife varies and consequently it is desirable to provide means for adjusting the heel tread plate relatively to the breasting knife in order that the heel tread plate may be positioned with its forward edge substantially adjacent the path of the breasting knife regardless of the curvature thereof. Means for adjustment of the heel tread plate relatively to the breasting knife is, therefore, provided. In the illustrated machine said means comprises a plate supporting slide 126 (Figs. 2, 8 and 9) having a T-guide formed lengthwise thereof for engagement within a T-way formed in a plate supporting bracket 128. As a convenient means for adjustment of the slide 126 a thumb screw 130 is threaded into a boss 132 extending upwardly from the rear end of the bracket 128 and centrally located relatively to the T-way. The slide 126 is extended rearwardly of the bracket 128 and is provided with an arcuate groove 134 having substantially the same curvature as the head of the thumb screw 130, the thumb screw and slide being arranged to permit engagement of the head of the screw in the groove 134 whereby movement of the screw effects an adjustment of the slide 126 relatively to the breast- ing knife. In order that the heel tread plate 32 may adjust itself to the tread of a heel to be breasted it is pivotally mounted in the slide 126.

by means comprising a semi-cylindrical boss 136 extending upwardly from the heel plate and arranged transversely thereof for engagement within a groove formed in the under surface of the slide 126. The boss 136 is held in engagement within said groove by a pin 138 extending upwardly from the center of the boss 136 through a slot 140 formed in the slide 126 and having upwardly diverging sides to permit a limited swinging movement of the pin 138. At its upper end the pin 138 is provided with a cross pin 142 which is supported upon the slide 126.

The heel stop 36 (Figs. 2, 5 and 6) consists of a block having pivot pins 144 illustrated as formed integrally thereon and arranged for engagement with suitable notches in the ends of a yoke 146 (Fig. 8). The heel stop is yieldingly held in engagement with the notched ends of the yoke 146 by a pair of coil springs 148 connecting the pivot pins 144 and a pair of studs 150 extending outwardly from the yoke 146. The heel stop is positioned beneath the heel tread plate 32 in a spaced relation thereto calculated to permit a sufficient movement of the heel stop to allow self-adjustment thereof relatively to the back of a heel to be breasted while preventing the heel stop from swinging by gravity into a downwardly facing position. In order to maintain the heel stop in operative position the yoke 146 in which the stop is pivotally mounted is supported upon the upper surface of the heel tread plate 32 by rolls 154 pivotally mounted in lugs 156 (Fig. 2) extending upwardly from the ends of the yoke 146 and arranged for rolling engagement with opposite margins of the heel tread plate 32. The yoke 146 has a shank 158 extending rearwardly therefrom and pivotally supported upon a pair of links 160 forming a part of the mechanism hereinafter described for locking the heel stop in heel engaging position.

In the illustrated machine pressure is applied to the shank presser 26 and the heel tread plate 32 by the power compressed spring 34 (Figs. 1 and 3) through connections including the sliding head 86 (Fig. 2), the presser post 84 slidably mounted therein, a heel plate post 162 which is also slidably mounted in the head 86, and a connecting rod 164 to which the sliding head 86 is secured and to which the pressure of the spring 34 is imparted.

The presser post 84 and heel plate post 162 are held against rotation by cross pins 163, 165 (Fig. 2) secured in the presser post and heel plate post, respectively. The rear end of the cross pin 163 is received within a groove 167 formed in the heel plate post 162 and extending downwardly from a point beneath the cross pin 165. The cross pin 163 is extended forwardly of the presser post 84 to provide means for holding the upper end of the treadle spring 92. The cross pin 163 also operates to support the heel plate post in its inoperative position whereby the heel of a shoe to be breasted is permitted to pass under the heel tread plate 32. The forward end of the cross pin 165 is received within a groove 169 formed in the presser post 84 and extending upwardly from a point above the cross pin 163.

The downward movement imparted to the sliding head 86 by the power spring 34 is transmitted to the presser post 84 and the heel plate post 162 through a pawl and ratchet mechanism comprising ratchet teeth 166 formed in the

presser post 84, ratchet teeth 168 formed in the heel plate plate post 162 and differential pawls 170 and 172 arranged for engagement with the ratchet teeth formed in the presser post and heel plate post, respectively. The ratchet teeth and their pawls are arranged to engage during the downward movement imparted to the sliding head 86 by the power spring 34. The pawls are mounted in pendants 176 (Figs. 2 and 15) 5 pivotally mounted upon a rocking carrier 178 which in turn is secured to a rod 180 carried by the sliding head 86. The pawls are arranged to slide in sockets 181 in the pendants 176 (Fig. 15) and are spaced apart a distance, measured 10 in terms of ratchet teeth, equal to one-half a tooth more than a prescribed number. The pawls 170 are actuated by compression springs 182 seated at the base of the sockets 181 and the range of movement of each pair of the pawls 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

(Fig. 3) secured to the driving shaft 40 by connections comprising a link 210 pivoted at its upper end to an arm 203 of the bell crank lever 202 and at its lower end to a horizontal arm of a bell crank lever 212. The vertical arm of the bell crank lever 212 carries a cam roll 214 arranged to ride on the cam 208. It will be seen that the cam roll 214 will be held toward the cam 208 by the tension of the spring 200 which acts on the pawl carrier 178. In order to elevate the sliding head 86 and at the same time to compress the power spring 34 a triangular lever 216 is arranged to actuate the connecting rod 164. The lever 216 is pivoted to the machine frame by a shaft 218 and carries at its lower end a cam roll 220 arranged to ride on a cam 222 secured to the shaft 40. At its forward extremity, as seen in Fig. 3, the lever 216 is pivoted to the lower end of the connecting rod 164. In order to provide a bearing for the bell crank lever 212 the shaft 224 connecting the triangular lever 216 and the connecting rod 164 is extended sufficiently to permit said lever to be pivoted thereto. In order to adjust the compression of the power spring 34 the collar 226 is threaded on the connecting rod 164 and provided with sockets 228 for the reception of a turning tool.

The timing of the cams 208 and 222 and the cam 108 which controls the clamping of the wing nut 46 is such that the cam 208 operates at the beginning of the power cycle to bring the pawls 170 into ratchet engaging position and thereupon the cam 222 operates to release the power spring 34, thereby permitting said spring to impart a downward pressure to the shank presser 26 and the heel tread plate 32, and after the power pressure has been effected the cam 108 operates to release the coiled spring 102, permitting the wing nut 46 to be brought into contact with the clamping block 76. The above-described timing of the cams 208, 222 and 108 is desirable since it insures that the stroke of the breasting knife will be measured from the final positions of the shank and heel tread after the pressing means has operated to take all the yield out of the sole and bring it down firmly against the last.

As herein illustrated, the jack 28 (Figs. 2 and 4) is mounted for straight line horizontal movement upon the jack carrier 30 (Fig. 4) which is slidably mounted upon the connecting rod 164 and yieldingly supported thereon by the compression spring 232 seated on the machine frame at 233 (Fig. 3). The connection between the jack and its carrier comprise a horizontal member, for example, the tube 234, mounted at the upper end of a vertical arm 236 formed integrally with the jack 28. The tube 234 is made rigid with the arm 236 by a strut 238 (Fig. 2) one end of which is supported in a socket formed at the rear of the jack base and the other end of which is received within a recess or hole formed in the tube 234. In order to permit rotation of the tube 234 and a corresponding swinging movement of the jack 28 whereby transverse adjustment of a shoe relatively to the breasting knife may be effected, the tube is supported upon guide rolls 240 and 242 pivoted to the jack carrier 30 and grooved for the reception of the tube. The roll 242 is positioned at the rear end of the carrier and above the tube 234 and the roll 240 is positioned beneath the tube and forwardly of the roll 242, thereby per-

mitting the tube to be held in engagement with the block 266 during the swinging of the links. Between the guide rolls by the weight of the jack. The jack carrier 30 is prevented from swinging about the connecting rod 164 by a bell crank lever 244 (Fig. 4) pivoted to the machine frame and having the end of its horizontal arm 248 pivoted to an extension of the stud 248 upon which the guide roll 240 is pivoted. The vertical arm 250 of the bell crank lever 244 is provided with an adjustable abutment screw 252 arranged to engage the machine frame in order to limit the upward movement of the jack carrier 30 by the spring 232. The forward movement of the jack 28 is limited by the engagement of the strut 238 with the guide roll 240. In its forward position the jack is prevented from swinging by the engagement of a pair of guide rolls 254 (Fig. 4) with horizontal ribs 256 formed in the base of the jack at opposite sides thereof. At their forward ends the ribs 256 are terminated rearwardly of the forward extremity of the jack base in order that said ribs may travel by the guide rolls 254 as the shoe is brought into the breasting position, thus permitting a swinging movement of the jack 28 within the limits prescribed by the guide rolls 254 and the forward extremity of the jack base. The guide rolls 254 may conveniently be pivoted upon pins 258 projecting upwardly from the ends of a yoke 260 (Fig. 1) which in turn is secured to the forward end of a lever 262 (Fig. 3) which operates to limit the downward movement of the jack under the thrust of the power spring 34 which takes effect after the jack has been moved in and the heel post 284 has been brought into alignment with the forward end of the lever 262. The lever 262 is pivoted at 263 to the machine frame. In order to prevent rotation of the yoke 260 a groove 264 (Fig. 4) is formed in its rear surface for engagement with the forward end of the lever 262. The movement of the lever 262 incidental to the downward movement of the jack 28 is arrested by the engagement of the links 160 with a clamping block 266 (Fig. 2). The links 160 connect the rearward end of the lever 262 and the shank 158 of the yoke 146. The upper ends of the links 160 are arranged to engage the clamping block 266 (Figs. 2 and 8) at opposite sides of its pivot 268, thereby insuring an equal clamping pressure of the links 160 against the clamping block 266.

The engagement of the base of the jack with the lever 262 as a shoe is clamped in breasting position by the power spring 34, operates to prevent displacement of the jack after the shoe has been so clamped, and the cutting thrust of the knife operates to increase the force of the clamping engagement of the jack upon said lever.

The action of the compression spring 34 upon the jack 28 also operates to lock the heel stop 36 in heel engaging position as a consequence of the connection of the yoke 146 with the links 160. In order to accommodate the clamping block 266 to the swinging movement of the links 160 incidental to the adjustment of the heel stop during the positioning of a shoe to be breasted, arcuate surfaces 267 (Fig. 2) are formed in the under side of the clamping block 266 for engagement with the ends of the links 160, the radius of curvature of said surfaces being substantially the same as the radius of an arc described by the ends of the links 160. Thus, it will be seen that a constant spaced relation is maintained between the upper ends of the links 160 and the under surface of the clamping block 266 during the swinging of the links. Between the arcuate surfaces 267 the clamping block 266 is extended downwardly to provide guiding surfaces 271 for the links 160. In order to prevent any play of the shank 158 of the yoke 146 between the inner surfaces of the links 160, a hub 273 (Fig. 8) is formed at the end of the shank 158 and positioned between the inner surfaces of the links 160. It is apparent that the clamping of the links 160 against the clamping block 266 will lock the heel stop 36 in adjusted position and prevent any movement thereof during the breasting operation. It may also be noted that the force of the clamping engagement of the links 160 with the clamping block 266 is increased by the cutting thrust of the knife.

The heel stop 36 is normally held at the forward limit of its movement by a coiled spring 269 (Figs. 2 and 3) connecting the links 160 and the lever 262. Said spring also operates to maintain the forward end of the lever 262 at the limit of its elevation which limit is prescribed by the engagement of an adjustable abutment screw 270 with the machine frame (Fig. 3). By adjusting the screw 270 the relative elevation of the base of the jack 28 and the upper surface of the lever 262 may be determined.

The jack 28 may be of any usual construction. As illustrated, the jack comprises a toe support 272 (Fig. 2) mounted on a shank 274 arranged to swing upon the jack arm 276. Vertical adjustment of the toe support 272 may be effected by sliding the shank 274 through the pivot block 278 and the toe support may be clamped in adjusted position by a hand screw 280 (Fig. 1) arranged to bring the shank 274 into clamping engagement with arcuate ribs 282 formed in the arm 276. The heel post 284 is mounted in a vertical hole in the jack base and supported therein by engagement of a shouldered surface of the post with a seat formed in an upwardly extending boss 286 formed in the jack base. The heel post 284 is provided at its upper end with a short tapered last pin 288 which permits a shoe to be maintained in a horizontal position during the swinging of the jack incidental to the transverse adjustment of the shoe relatively to the breasting knife.

In order to adjust the preliminary elevation of the knife to permit its cutting edge to be employed as a gage to determine the breasting position of a shoe, a stop 287 is provided (Fig. 1) for determining the limit of the upward movement of the knife actuator 24 by the torsion spring. The stop 287 is adjusted vertically by a hand screw 289 mounted in a tapped hole in a bracket 290 extending forwardly from the machine frame. The screw 289 is inclined outwardly in order to provide sufficient clearance for a hand wheel 292 secured at its upper end. The stop 287 has a yoke 296 formed integrally therewith and pivoted to the screw 289. The stop 287 is preferably arranged to engage the hub of one of the links 80 which connect the torsion spring 50 and the actuator 24.

Referring now to the clutching mechanism (Figs. 1 and 3), a clutch 300 of any usual construction, for example, one of the Horton type, is provided for connecting the wheel 38 and the driving shaft 40. When the machine is at rest the clutch 300 is maintained in unclutched condition by a stop arm 302 secured to a rock shaft 304 and arranged to engage under a projection 306 of the clutch 300. The stop arm 302 is

disengaged from the projection 306 by the treadle 90 after the treadle has brought the shank presser 26 into shank engaging position. The stop arm 302 is automatically returned to operative position before the driving shaft 40 has completed one rotation. The return of the stop arm 302 is effected by mechanism comprising a cam 308 (Fig. 1) secured to the driving shaft 40 and arranged to straighten the toggle 310, 312 by engagement with an extension 314 of the toggle link 312. Straightening of the toggle swings an arm 316 secured to the rock shaft 304 rocking said shaft in a direction to return the stop arm 302 into position to be engaged by the projection 306 of the clutch 300 when said projection reaches its starting position. In order that the treadle 90 may operate to break the toggle 310, 312 and thereby actuate the rock shaft 304 to disengage the stop arm 302 from the projection 306, a catch lever 318 is pivoted on the toggle bearing 320 and arranged to be engaged by a plate 322 secured to the treadle. The engagement of the plate 322 with the catch lever 318 is timed to take effect after the treadle 90 has brought the shank presser into engagement with the shank of the shoe to be breasted. The catch lever is maintained in position to be engaged by the plate 322 by a spring 324 which operates to maintain the upwardly extending arm 30 of the catch lever in engagement with the hub of the toggle link 310. The spring 324 also operates to maintain the toggle in a straightened condition determined by the engagement of the abutment screw 326 carried by the toggle link 310 with a stop 328 formed in the machine frame. In order to disengage the catch lever 318 from the plate 322 and permit the straightening of the toggle in advance of the retraction of the treadle, the catch lever is provided at its upper end with a pin 330 extending forwardly into a position to be engaged by the cam 308 at an early stage in the rotation of the driving shaft.

The rotating assembly is brought to rest at the end of a cycle of operations by a brake shoe 332 arranged to be engaged by an eccentric 334 fixed to the driving shaft 40. The brake shoe is pressed against the eccentric 334 by a spring 336 connecting the brake lever 338 and the machine frame, the range of movement of the lever 338 being limited by a sleeve 340 carried by the spring 336 and arranged to abut the stud 342.

The operation is as follows: Preliminary to the depression of the treadle 90 the breasting knife 20 may be adjusted by the hand wheel 292 to bring the cutting edge of the knife into the desired elevation for gaging the breasting position of the shoe to be operated upon. The jack 28 is then moved rearwardly of the machine with a shoe to be breasted mounted thereon. (For the purpose of illustration let it be assumed that the shoe to be breasted is a lady's shoe having a heel of average height). If desired, the shoe is now adjusted transversely of the knife by swinging the jack about its fulcrum 234. The treadle 90 may now be operated to depress the actuator 24 thereby permitting the descent of the breasting knife 20, the shank presser 26 and the heel tread plate 32. The movements of the breasting knife and the heel tread plate are arrested by the heel tread. The actuator 24 and the knife slide 56 are now in the position illustrated in Fig. 11. After the breasting knife and heel plate have been arrested by engagement with the heel tread, the shank presser 26 descends alone until the

presser foot engages the shank. Depression of the actuator, after the descent of the breasting knife has been arrested, causes the actuator to slide through the grooves 66 formed in the knife slide, the extent of such sliding movement depending upon the height of the heel to be breasted and the adjustment of the breasting knife. At the termination of said sliding movement the actuator 24 is positioned, relatively to the knife slide 56, as shown in Fig. 12, the position of the slide remaining the same as in Fig. 11. Continued depression of the treadle 90 after the shank presser has been brought into contact with the shoe breaks the toggle 310, 312 thereby rocking the shaft 304 and thus disengaging the stop arm 302 from the clutch 300 and permitting the clutch to connect the wheel 38 to the shaft 40. During the initial stage of the rotation of the driving shaft 40 the pawl carrier 178 is actuated by its cam 208 to bring the pawls 170 into operative position, and thereupon the cam 222 releases the spring 34 sufficiently to permit it to clamp the shank presser and heel plate upon the shoe to be breasted. The clamping pressure imparted to the presser and heel plate by the spring 34 operates to bring the base of the heel post 284 into clamping engagement with the upper surface of the lever 262 at its forward end, and through the actuation of said lever, the spring 34 operates to bring the links 160 into clamping engagement with the clamping block 266. At this stage in the operation of the machine the actuator 24 is in a position relative to the knife slide 56 such as that shown in Fig. 13, the actuator having advanced from its position, as shown in Fig. 12, an amount equal to the depression of the shank presser 26 by the spring 34. During the continued rotation of the driving shaft after the clamping operations have been effected the cam roll 110 rides off the rise of the cam 108 thereby permitting the spring 102 to bring the wing nut 46 into contact with the clamping block 76, and the downward movement of the clamping block with the crank pin 42 clamps the nut 46 to the block thereby providing an unyielding connection between the crank pin 42 and the knife actuator 24. The actuator 24 is now advanced by the crank pin 42, first traversing its lost motion (indicated at A in Fig. 13), and during the remainder of the advancing stroke of the crank pin, imparting a measured cutting thrust to the breasting knife. It will be seen that the knife decelerates as the crank pin 42 approaches the bottom of its stroke and comes to rest as the crank pin arrives at dead center. Consequently, the knife slide has no appreciable momentum as it comes to rest at the end of its advancing stroke and, therefore, there is no tendency of the knife slide to overthrow and carry the breasting knife beyond the base of the heel. The actuator and knife slide are now in the position illustrated in Fig. 14. During the return of the crank pin from dead center to its initial position the clamping block 76 travels slightly in advance of the wing nut 46 leaving the nut free to rotate upon the screw 44 in order to return to its elevated position. During the same interval the cam roll 214 rides off the rise of the cam 208, thereby permitting the spring 200 to retract the pawl carrier 178, thus disengaging the pawls 170 from their ratchets. After the retraction of the pawls 170 the torsion spring 50 operates to retract the knife actuator 24 and with it the breasting knife 20,

- the shank presser 26 and the heel tread plate 32. As the driving shaft 40 approaches the end of its rotation, the cam 222 actuates the triangular lever 216 to return the sliding head 86 and 5 the pawl assembly to elevated position, and simultaneously to compress the spring 34. As the crank pin 42 arrives at its initial position, the stop arm 302 engages the projection 306 of the clutch 300, thereby disconnecting the wheel 38 10 from the driving shaft 40, and at the same time the eccentric 334 engages the brake shoe 332 and arrests the movement of the rotating assembly.
- Having thus described our invention, what we claim as new and desire to secure by Letters 15 Patent of the United States is:
1. In a heel breasting machine, a breasting knife, and a knife actuator arranged to provide a variable lost motion between the actuator and the knife at the beginning of the stroke of 20 the actuator.
  2. In a heel breasting machine, a breasting knife, and a constant stroke knife actuator arranged to provide a measured lost motion between the actuator and the knife at the beginning of the stroke of the actuator.
  3. In a heel breasting machine, a breasting knife, a knife actuator having a constant stroke, and connections between the actuator and the knife for imparting a variable stroke to the 25 knife, said knife stroke terminating simultaneously with the stroke of the actuator.
  4. In a heel breasting machine, a breasting knife, a knife support, a knife actuator arranged to impart a variable stroke to the knife support, 30 said stroke terminating simultaneously with the stroke of the actuator.
  5. In a heel breasting machine, a breasting knife, a driver for imparting a variable stroke, to the knife, and connections between the driver 35 and the knife whereby the knife comes to rest at one limit of the stroke of the driver.
  6. In a heel breasting machine, a breasting knife, a crank for imparting a variable stroke to the knife, and connections between the crank 40 and the knife whereby the knife comes to rest as the crank comes to one limit of its stroke.
  7. In a heel breasting machine, a breasting knife, a crank for imparting a variable stroke to the knife, and connections between the crank 45 and the knife whereby the knife decelerates as it approaches the limit of the breasting cut and comes to rest as the crank comes to one limit of its stroke.
  8. In a power operated heel breasting machine, 50 a breasting knife, a knife actuator having a constant power stroke, connections between the actuator and the knife for imparting a variable stroke to the knife, said knife stroke terminating simultaneously with the stroke of the actuator, and connections between the actuator and the shank of the shoe to be breasted for predetermining the position from which the power stroke 55 of the actuator commences.
  9. In a heel breasting machine, a breasting knife, a knife actuator having a constant stroke, 60 connections between the actuator and the knife for imparting a variable stroke to the knife, a shank engaging means, and connections between said shank engaging means and the actuator for predetermining the position from which the actuator operates.
  10. In a heel breasting machine, a breasting knife, a knife support, means for adjusting the knife relatively to its support, a knife actuator 65 having a constant stroke, connections between 70 the actuator and the knife for imparting a variable stroke to the knife, a shank engaging member, and connections between said member and the actuator operable in conjunction with said knife adjusting means to predetermine the position from which the actuator operates.
  11. In a heel breasting machine, a breasting knife, a slide in which the knife is secured, a knife actuator having a constant stroke, connections between the actuator and the slide for imparting a variable stroke to the slide, a shank engaging member, and connections between said member and the actuator for predetermining the position from which the actuator operates.
  12. In a heel breasting machine, a breasting knife, a knife actuator, a shank engaging member, and connections from said member for measuring, in advance of the knife stroke, the effective stroke of the actuator.
  13. In a heel breasting machine, a breasting knife, a knife slide, and a knife actuator mounted in said slide and arranged for measured movement relatively to said slide.
  14. In a heel breasting machine, a breasting knife, a knife actuator, means for adjusting the actuator in the direction of its stroke, and a knife slide upon which said actuator operates, said actuator and slide being arranged for relative movement in the direction of the knife stroke.
  15. In a heel breasting machine, a breasting knife, a knife actuator, means for adjusting the actuator in the direction of its stroke, a knife slide upon which said actuator operates, said actuator and slide being arranged for relative movement in the direction of the knife stroke, and means for determining the limit of the adjustment of the actuator.
  16. In a heel breasting machine, a breasting knife, a knife actuator arranged to be adjusted in the direction of its stroke and a shank engaging member arranged to measure the adjustment of the actuator.
  17. In a heel breasting machine, a breasting knife, a knife actuator arranged for adjustment in the direction of its stroke, and a knife supporting slide supported in its retracted position by said actuator and arranged to descend with the actuator during its adjustment until the knife is arrested by the heel tread.
  18. In a heel breasting machine, a breasting knife, a knife actuator arranged for adjustment in the direction of its stroke, a knife supporting slide supported in its retracted position by said actuator and arranged to descend with the actuator during its adjustment until the knife is arrested by the heel tread, and means for adjusting the knife relatively to the slide in order to vary the point in the adjustment of the actuator when the knife is arrested by the heel tread.
  19. In a power operated heel breasting machine, a breasting knife, a knife actuator, manually operated means for adjusting the actuator in the direction of its stroke, a driver, and means for connecting the actuator to said driver.
  20. In a power operated heel breasting machine, a breasting knife, a knife actuator, a driver, means for connecting the actuator to said driver comprising a screw carried by the actuator, a nut carried by said screw, connections between said driver and said nut, and means for locking the nut upon said screw.

21. In a power operated heel breasting machine, a breasting knife, a knife actuator, manually operated means for adjusting the actuator in the direction of its stroke, a driver, and connections between the driver and the actuator comprising a screw carried by the actuator, a nut carried by the screw and arranged to be rotated by the actuator during its adjustment, and a connecting link between said driver and said nut whereby said nut is locked against rotation thus connecting said link to said screw.
22. In a power operated heel breasting machine, a breasting knife, a knife actuator, a driver, connections between the driver and the actuator comprising a screw carried by the actuator, a nut carried by the screw, a link carried by the driver and supported upon the screw, inter-engaging clamping surfaces formed in the link and the nut, means for holding said clamping surfaces disengaged, and yielding means for urging said clamping surfaces into clamping relation.
23. In a power operated heel breasting machine, a breasting knife, a knife actuator, a driver, connections between the driver and the actuator comprising a screw carried by the actuator, a nut carried by the screw, a link carried by the driver, interengaging clamping surfaces formed in the link and the nut, cam actuated means for holding said clamping surfaces disengaged, and yielding means for urging said clamping surfaces into clamping relation.
24. In a power operated heel breasting machine, a shank presser, means energized by the next preceding cycle of the machine and normally disconnected from said presser for applying pressure thereto, and means for connecting said presser to said pressure applying means at the beginning of the power cycle.
25. In a heel breasting machine, a breasting knife, a knife actuator, a shank presser, and means energized by the next preceding cycle of the machine for applying pressure to said presser before the stroke of the actuator commences.
26. In a power operated heel breasting machine, a shank presser, a presser post, means energized by the next preceding cycle of the machine for applying pressure to said post, and means for connecting said post to said pressure applying means at the beginning of the power cycle.
27. In a power operated heel breasting machine, a shank presser, a presser post, means for applying power produced pressure to said post, and means for connecting said post to said pressure applying means at the beginning of the power cycle comprising a pawl and ratchet connection normally held disengaged, and power operated means for engaging said pawl and ratchet.
28. In a heel breasting machine, a shank presser, a presser post, a heel tread plate, a heel plate post, and connections from the presser post for supporting the heel plate post and for preventing rotation of the presser post.
29. In a heel breasting machine, a shank presser, a presser post, a support in which said post is slidably mounted, connections between said support and a source of power, and means for releasably connecting said support and said post.
30. In a heel breasting machine, a shank presser, a presser post, a head in which said post is slidably mounted, connections between said head and a source of power, and pawl and ratchet connections between said head and said post.
31. In a heel breasting machine, a shank presser, a presser post, a head in which said post is slidably mounted, a ratchet formed in said post, a pawl arranged for engagement with said ratchet, a pawl carrier mounted in said head, means for actuating said carrier to engage said pawl and ratchet, and means for actuating said head.
32. In a heel breasting machine, a shank presser, a presser post, a head in which said post is slidably mounted, a ratchet in said post, a pawl arranged for engagement with said ratchet, and means for disengaging said pawl from said ratchet.
33. In a power operated heel breasting machine, a shank presser, a heel tread plate, and means for applying equal power produced pressures to said presser and plate.
34. In a power operated heel breasting machine, a shank presser, a heel tread plate, and a power actuated spring for applying distributed pressure to said presser and plate.
35. In a power operated heel breasting machine, a shank presser, a heel tread plate, and a power actuated spring for applying equal pressure to said presser and plate.
36. In a heel breasting machine, a shank presser, a heel tread plate, means for applying pressure to said presser and plate, and means for equalizing the pressure applied to said presser and plate.
37. In a heel breasting machine, a shank presser, a presser post, a heel tread plate, a heel plate post, and means for applying distributed pressure to said posts.
38. In a heel breasting machine, a shank presser, a presser post, a heel tread plate, a heel plate post, a head in which said posts are slidably mounted, connections between said head and a source of power, and releasable connections between said head and said posts.
39. In a heel breasting machine, a shank presser, a presser post, a heel tread plate, a heel plate post, a head in which said posts are slidably mounted, connections between said head and a source of power, and pawl and ratchet connections between said head and said posts.
40. In a heel breasting machine, a shank presser, a presser post, a heel tread plate, a heel plate post, a head in which said posts are slidably mounted, a link connecting said head to a source of power, and pawl and ratchet connections between said head and said posts including a pawl carrier arranged for movement to equalize the pressure exerted on said pawls.
41. In a heel breasting machine, a shank presser, a presser post, a heel tread plate, a heel plate post, a head in which said posts are slidably mounted, ratchets on each of said posts, pawls arranged for engagement with said ratchets, a pawl carrier mounted in said head, a link secured to said head, and means for applying pressure to said link.
42. In a heel breasting machine, a shank presser, a presser post, a heel tread plate, a heel plate post, a head in which said posts are slidably mounted, ratchets in each of said posts, pawls arranged for engagement with said ratchets, a pawl carrier mounted in said head, a link secured to said head, means for applying pressure to said link, and means for disengaging said pawls from their respective ratchets.
43. In a heel breasting machine, a shank

- presser, a presser post, a heel tread plate, a heel plate post, a head in which said posts are slidably mounted, and means for securing said posts against upward movement comprising ratchets on said posts, pawls for engaging said ratchets, pendants in which said pawls are mounted, a pawl carrier on which said pendants are pivoted, said carrier being so mounted in said head that a downward pressure imparted to 5 said head imparts an equal pressure to said pawls.
44. In a heel breasting machine, a shank presser, a presser post, a heel tread plate, a heel plate post, a head in which said posts are slidably mounted, means for securing said posts against upward movement comprising ratchets on said posts, pawls for engaging said ratchets, pendants in which said pawls are mounted, a pawl carrier on which said pendants are pivoted, 10 means for maintaining said pendants in alignment with said posts, and means for pivotally mounting said carrier on said head whereby a downward pressure imparted to said head imparts an equal pressure to said pawls.
45. In a heel breasting machine, a shank presser, a presser post, a heel tread plate, a heel plate post, a head in which said posts are slidably mounted, and means for securing 15 said posts against upward movement comprising ratchets on said posts, pawls for engaging said ratchets, pendants in which said pawls are mounted, a pawl carrier on which said pendants are pivoted, guides formed in said pendants for engagement with said posts whereby said pendants are maintained in alignment with said posts.
46. In a heel breasting machine, a shank presser, a presser post, a heel tread plate, a heel plate post, a head in which said posts are slidably mounted, connections between said posts and said head comprising ratchets in said posts, pawls for engaging said ratchets, a pawl carrier in which said pawls are mounted at opposite sides thereof, and a carrier shaft mounted 20 in said head and arranged midway between said pawls.
47. In a power operated heel breasting machine, a shank presser, a heel tread plate, means for applying power produced pressure to said presser and plate, and means for connecting said presser and plate to said power applying means at the beginning of the power cycle.
48. In a power operated heel breasting machine, a shank presser, a presser post, a heel tread plate, a heel plate post, means for applying power produced pressure to said posts, and means for connecting said posts to said pressure applying means at the beginning of the power cycle.
49. In a power operated heel breasting machine, a shank presser, a presser post, a heel tread plate, a heel plate post, means for applying power produced pressure to said posts, means for connecting said posts to said pressure applying means at the beginning of the power cycle comprising pawl and ratchet connections normally held disengaged, and power operated means for engaging said pawls and their ratchets.
50. In a power operated heel breasting machine, a shank presser, a presser post, a heel tread plate, a heel plate post, means for applying power produced pressure to said posts, means for connecting said posts to said pressure applying means at the beginning of the power cycle.
51. In a power operated heel breasting machine, a shank presser, a presser post, a heel tread plate, a heel plate post, a head in which said posts are slidably mounted, ratchets on said posts, pawls carried by said head and arranged for engagement with said ratchets, yielding means for holding said pawls out of ratchet engaging position, and power operated means for bringing said pawls into ratchet engaging position.
52. In a heel breasting machine, a breasting knife, a knife slide in which the breasting knife is mounted, yielding means for holding the knife slide in retracted position, and means for adjusting the retracted position of the slide.
53. In a heel breasting machine, a breasting knife, a knife slide in which the breasting knife is mounted, a spring for retracting the slide, a stop for limiting the operation of the spring, and means for adjusting the stop in order to vary the retracted position of the slide.
54. In a heel breasting machine, a shoe supporting jack yieldingly supported and arranged for straight line movement toward and from operative position.
55. In a heel breasting machine, a shoe supporting jack, a jack carrier arranged to permit rotation of the jack about a horizontal axis extending longitudinally of the jack, and shoe bottom engaging means for clamping a shoe on the jack and thus holding the jack from rotating during the breasting operation.
56. In a heel breasting machine, a breasting knife, a shoe supporting jack, a jack carrier arranged to permit a limited swinging movement of the jack whereby a jacked shoe is rendered laterally adjustable with relation to the breasting knife, and a heel plate arranged to engage the heel of the jacked shoe and thereby to hold the jack from swinging during the breasting operation.
57. In a heel breasting machine, a shoe supporting jack yieldingly supported upon the machine frame and arranged for straight line movement to carry a jacked shoe into and out of breasting position, and a stop for limiting downward movement of the jack.
58. In a heel breasting machine, a shoe supporting jack, a jack carrier, and connections between the jack and the carrier comprising a cylindrical member secured to the jack and rollers journaled in the carrier constructed and arranged to permit rotation of said cylindrical member.
59. In a heel breasting machine, a shoe supporting jack, a jack carrier arranged to permit rotation of the jack about a horizontal axis extending longitudinally of the jack means for preventing such rotation when the jack is out of breasting position, and means for limiting such rotation when the jack is in breasting position.
60. In a heel breasting machine, a shoe supporting jack arranged for rotation about a horizontal axis extending longitudinally thereof, and members arranged to engage opposite sides of the jack whereby such rotation is prevented when the jack is out of breasting position and limited when the jack is in breasting position.
61. In a heel breasting machine, a shoe sup-

- porting jack arranged for rotation about a horizontal axis extending longitudinally thereof, and a pair of rollers arranged to engage the base of the jack at opposite sides thereof in order to limit such rotation.
62. In a heel breasting machine, a shoe supporting jack arranged for rotation about a horizontal axis extending longitudinally thereof, means for preventing such rotation when the jack is out of breasting position comprising ribs formed at the base of the jack, and a pair of rollers arranged to engage said ribs, said ribs being terminated at their forward extremities in order to permit a limited swinging movement 10 of the jack when in breasting position.
63. In a heel breasting machine, means for supporting a shoe in breasting position, comprising a toe support, a heel support, and a heel stop arranged partially to embrace the back of a heel to be breasted.
64. In a heel breasting machine, means for supporting a shoe in breasting position, comprising a toe support, a heel support, and a heel stop arranged to engage the back of the heel and 15 yieldingly urged thereagainst.
65. In a heel breasting machine, means for supporting a shoe in breasting position comprising a toe support, a heel support, a stop arranged to engage the back of a heel, and 20 means actuated by the cutting thrust of the knife to lock the stop in heel engaging position.
66. In a heel breasting machine, means for supporting a shoe in breasting position including a heel stop constructed and arranged for 25 engagement with the back of the heel to be breasted, yielding means for urging the stop toward the heel, and means for securing the stop in heel engaging position.
67. In a heel breasting machine, means for supporting a shoe in breasting position including a heel stop constructed and arranged for 30 engagement with the back of the heel to be breasted, yielding means for urging the stop toward the heel, and means actuated by the cutting thrust of the knife for locking the stop in heel engaging position.
68. In a heel breasting machine, means for supporting a shoe in breasting position including a stop constructed and arranged for engagement with the back of the heel to be 35 breasted, means for clamping the stop in heel engaging position comprising clamping elements, and means actuated by the cutting thrust of the knife for imparting a clamping action to said clamping elements.
69. In a heel breasting machine, means for supporting a shoe in breasting position including a stop constructed and arranged for engagement with the back of the heel to be 40 breasted, means for clamping the stop in heel engaging position comprising clamping elements one of which is movable with the stop, connections between the stop and said movable element, and a jack supporting lever connected at 45 one end to said movable clamping element whereby the cutting thrust of the knife imparts a clamping action to said clamping elements.
70. In a heel breasting machine, means for supporting a shoe in breasting position including a stop constructed and arranged for engagement with the back of a heel to be breasted, and means for clamping the stop in shoe engaging 50 position comprising relatively adjustable clamping elements, and connections between the stop and one of said elements whereby said clamp- 55 ing elements are adjusted by a movement imparted to the stop.
71. In a heel breasting machine, means for supporting a shoe in breasting position including a stop constructed and arranged for engagement with the back of a heel to be breasted and normally held at the forward limit of its movement, means for clamping the stop in shoe engaging position comprising relatively adjustable clamping elements, and connections between the stop and one of said elements whereby said clamping elements are adjusted by a movement imparted to the stop.
72. In a heel breasting machine, a heel tread plate for engagement with the tread of the heel to be breasted, and means for supporting a shoe in breasting position comprising a toe support, a heel support, and a heel stop constructed and arranged partially to embrace the back of a heel to be breasted and supported upon the heel tread plate.
73. In a heel breasting machine, a heel stop arranged to engage the back of a heel to be breasted and arranged for self adjustment to the inclination of the rear face of the heel.
74. In a heel breasting machine, a heel stop arranged to engage the back of a heel to be breasted, and a carrier in which the stop is pivotally mounted whereby the stop is self adjusting to the slope of heel.
75. In a heel breasting machine, a heel stop arranged to engage the back of a heel to be breasted, a carrier in which the stop is pivotally mounted, and means for limiting the rotation of the stop whereby the heel engaging surface is always presented to the heel.
76. In a heel breasting machine, a heel tread plate, a heel stop arranged to engage the back of a heel to be breasted, a carrier in which the stop is pivotally mounted, and supporting connections between said carrier and heel tread plate.
77. In a heel breasting machine, a shoe supporting jack, and means for clamping a shoe upon the jack comprising a shank presser, a heel tread plate, and a heel stop.
78. In a heel breasting machine, a shoe supporting jack, and means for clamping a shoe upon the jack, comprising a shank presser, a heel tread plate, a heel stop, means for simultaneously actuating said presser and plate, and means for yieldingly urging the stop against the back of the heel.
79. In a heel breasting machine, a shoe supporting jack, and means for clamping a shoe upon the jack, including a shank presser, a heel stop, means for actuating said presser, and means for yieldingly urging the stop against the back of the heel.
80. In a heel breasting machine, a shoe supporting jack, means for clamping the shoe upon the jack including a heel stop, and yielding means for urging the stop against the back of the heel.
81. In a heel breasting machine, heel engaging means arranged to engage the back of a heel to be breasted, and yielding means whereby the heel engaging means is positioned to be engaged by the heel as it advances into breasting position.
82. In a heel breasting machine, a heel engaging member arranged to engage the back of a heel to be breasted, yielding means whereby said member is positioned to be engaged by the heel as it advances into breasting position, and

means for locking said member after the shoe has been brought into breasting position.

83. In a heel breasting machine, a breasting knife, a heel stop arranged to engage the back of a heel to be breasted, yielding means whereby the stop is positioned to be engaged by the heel as it advances into breasting position, and means actuated by the cutting thrust of the knife for locking the stop after the shoe has been brought into breasting position.

84. In a heel breasting machine, a shoe supporting jack, and means for clamping a shoe thereon comprising a shank presser, power operated means for actuating said presser, and a heel stop arranged to engage the back of the heel and yieldingly urged thereagainst.

85. In a heel breasting machine, a shoe supporting jack, and means for clamping a shoe thereon comprising a shank presser, a heel tread plate, means for simultaneously applying a clamping pressure to said presser and plate, and a heel stop arranged to engage the back of the heel and yieldingly urged thereagainst.

86. In a heel breasting machine, a shoe supporting jack, means for clamping a shoe thereon comprising a shank presser, a heel tread plate, means for applying an equal clamping pressure to said presser and plate, and a heel stop arranged to engage the back of the heel and yieldingly urged thereagainst.

87. In a heel breasting machine, a shoe supporting jack, a heel stop, and means actuated by the cutting thrust of the knife for locking the heel stop in heel engaging position.

88. In a heel breasting machine, a shoe supporting jack, a heel stop, and means actuated by the cutting thrust of the knife for simultaneously clamping the jack in breasting position and locking the heel stop in heel engaging position.

89. In a heel breasting machine, a shoe supporting jack, a heel stop, means actuated by the cutting thrust of the knife for simultaneously clamping the jack in breasting position and locking the heel stop in heel engaging position, said means comprising a lever arranged to be actuated by the jack, clamping surfaces formed in the lever and jack, clamping devices arranged to be actuated by said lever, and connections between said devices and the heel stop.

90. In a heel breasting machine, a shoe supporting jack, a heel stop arranged to engage the back of a heel to be breasted and yieldingly held in position to be engaged by the heel as the shoe is brought into breasting position, and means actuated by the cutting thrust of the knife for simultaneously clamping the jack in breasting position and locking the stop in heel engaging position.

91. In a heel breasting machine, a breasting knife, a shank presser, a heel tread plate, and yielding means for holding said members in retracted position.

92. In a heel breasting machine, a breasting knife, a knife actuator, yielding means for holding the actuator in retracted position, connections between the actuator and the knife for holding the knife in retracted position, a shank presser, and connections between the actuator and the presser for holding the presser in retracted position.

93. In a heel breasting machine, a breasting knife, a knife actuator, yielding means for holding the actuator in retracted position, a shank presser, a presser post, connections between said

post and the actuator for holding the presser in retracted position, a heel tread plate, and connections between the heel tread plate and said post for holding the plate in retracted position.

94. In a heel breasting machine, a breasting knife, a knife actuator, a driver for imparting a constant stroke to said actuator, yielding means mounted on the driver for holding the actuator in retracted position, connections between the actuator and the knife for holding the knife in retracted position, a shank presser, a presser post, connections between the actuator and said post for holding the presser in retracted position, a heel tread plate, and connections between said post and the heel tread plate for holding the plate in retracted position.

95. In a power operated heel breasting machine, a shank presser, a spring for actuating said presser, and power actuated means for energizing said spring at the end of the machine cycle.

96. In a power operated heel breasting machine, a breasting knife, a shank presser, a spring for actuating said presser, and power actuated means for energizing said spring during the retracting stroke of the knife.

97. In a power operated heel breasting machine, a breasting knife, a shank presser, yielding means for actuating said presser, a driver, and connections from the driver for compressing said yielding means during the retracting stroke of the knife.

98. In a power operated heel breasting machine, a breasting knife, a shank presser, actuating means therefor, and a driver for successively releasing said presser actuating means and actuating said knife.

99. In a power operated heel breasting machine, a breasting knife, a shank presser, a spring, means operable to connect the spring and the presser, and a driver for successively actuating said connecting means, releasing said spring and actuating said knife.

100. In a power operated heel breasting machine, a breasting knife, a shank presser, a spring, means operable to connect the spring and the presser, and a driver for successively actuating said connecting means, releasing said spring, actuating said knife, and energizing said

101. In a power operated heel breasting machine, a breasting knife, a knife actuator, a driver therefor, and a treadle for successively imparting a preliminary adjustment to said actuator and connecting said driver to a source of power.

102. A heel breasting machine having, in combination, a breasting knife, a shoe supporting jack arranged for straight line movement to bring a jacked shoe into position to be operated upon by the knife and arranged for movement to permit lateral adjustment of the shoe relatively to the knife, a shank presser, a heel tread plate, means for applying pressure to said presser and plate, a knife actuator, a driver therefor, and connections between the actuator and the knife for imparting a variable stroke thereto.

103. A heel breasting machine having, in combination, a breasting knife, a shoe supporting jack arranged for movement to bring a jacked shoe into position to be operated upon by the knife, a shank presser, a heel tread plate, means for applying power pressure to said presser and plate, a knife actuator, a driver therefor, and

connections between the actuator and the knife for imparting a variable stroke thereto.

104. A heel breasting machine having, in combination, a breasting knife, a shoe supporting

5 jack, means for preliminary adjustment of the knife in the direction of its stroke, a shank presser, a heel tread plate, means for applying pressure to said presser and plate, and means for imparting a variable stroke to the knife.

105. A heel breasting machine having, in combination, a breasting knife, a shoe supporting jack, a shank presser, a heel tread plate, means for imparting equal pressure to said presser and plate, means for varying said pressure, and 10 means for actuating the knife.

106. A heel breasting machine having, in combination, a breasting knife, a shoe supporting jack, a shank presser, a heel tread plate, an actuator for imparting a variable stroke to the 15 knife, and yielding means for holding the knife, the actuator, the presser and the heel tread plate in retracted position.

107. A heel breasting machine having, in combination, a breasting knife, a shoe supporting

20 jack, a shank presser, a heel tread plate, an actuator for imparting a variable stroke to the knife, yielding means for holding the knife, the actuator, the presser and the heel tread plate in retracted position, and means for limiting the 25 operation of said yielding means in order to predetermine the retracted positions of said members.

108. A heel breasting machine having, in com-

bination, a breasting knife, a shoe supporting jack, means for clamping a shoe on the jack comprising a shank presser, a heel tread plate, a heel stop, means for applying pressure to said presser, plate and stop, and means for imparting a variable stroke to the knife.

5

109. A heel breasting machine having, in combination, a breasting knife, shoe supporting means comprising a toe support, a heel support and a heel stop, a knife actuator, driving means therefor, and connections between the actuator and the knife for imparting a variable stroke thereto.

10

110. A heel breasting machine having, in combination, a breasting knife, a shoe supporting 15 jack arranged for movement to bring a jacked shoe into position to be operated upon by said knife, a shank presser, means for imparting pressure thereto, a knife actuator, and connections between the presser and the actuator for 20 measuring the effective stroke of the actuator.

111. A heel breasting machine having, in combination, a breasting knife, a shoe support, a shank presser, means for applying pressure thereto, a knife actuator, connections between 25 the presser and the actuator for measuring the effective stroke of the actuator, a driver for the actuator, and means for connecting the driver and the actuator at a predetermined point in the operative cycle.
